T. G. SELLECK,

CHARGING TRUCK,

APPLICATION FILED JAN. 20, 1919.

Patented Dec. 23, 1919.

UNITED STATES PATENT OFFICE.

THEODORE G. SELLECK, OF MOLINE, ILLINOIS, ASSIGNOR TO DEERE & COMPANY, OF MOLINE, ILLINOIS, A CORPORATION OF ILLINOIS.

CHARGING-TRUCK.

1,326,001.

Specification of Letters Patent. Patented Dec. 23, 1919.

Application filed January 29, 1919. Serial No. 272,163.

To all whom it may concern:

Be it known that I, THEODORE G. SELLECK, a citizen of the United States, residing at Moline, in the county of Rock Island, State 5 of Illinois, have invented certain new and useful Improvements in Charging-Trucks, of which the following is a specification, reference being had to the accompanying drawings.

10 In connection with the carbonizing of sheets or plates it has been discovered that for some uses such sheets or plates are best introduced into the heating chamber of the furnace in a vertical position and separated 15 from each other, and there left in such position so that after they have been subjected to a predetermined amount of heat the desired carbonizing material may be placed in the chamber and fill in the spaces between 20 the parallel rows of sheets or plates thus standing on their edges and the spaces between the side walls of the chamber and the outermost sheets or plates. It is the object 25 of my invention to provide a charging truck that will carry a plurality of sheets or plates on edge and separated from each other, and that, after being moved into the heating chamber, can be readily withdrawn from beneath 30 its load and leave the sheets or plates on the floor of said chamber and in the same edgewise and separated positions as when loaded on the truck. This object I accomplish as illustrated in the drawings and hereinafter described. That which I believe 35 to be new and desire to cover by this application will be set forth in the claims.

In the drawings:

Figure 1 is a plan view of my improved truck partly-loaded with a number of sheets or plates arranged in the manner in which 40 they are to be left on the floor of a furnace heating chamber;

Fig. 2 is a side elevation of the partly-loaded truck of Fig. 1;

45 Fig. 3 is a vertical longitudinal section taken at line 3—3 of Fig. 1; and

Fig. 4 is a detail of the spreader or plate-spacing device that holds the sheets or plates upright and spaced apart after the truck 50 has been withdrawn from beneath them.

Referring to the several figures of the drawings,—10—10 indicate the side bars of the truck which at their forward ends are

connected together by a cross-bar 11, which, as shown, is riveted thereto. At intervals 55 said side bars are also secured together by braces 12, the different braces being secured in place preferably by riveting to the side bars. Near their rear ends the side bars are further connected together in the construction shown by a cross-tie 13 on which is mounted a spacing pipe 14, the ends of which will abut against the inner faces of the side bars. 15 indicates a plurality of rollers—four being employed in the construction shown—upon which the truck frame is removably supported. The ends 60 of these frame-supporting rollers are suitably journaled in plates 16 secured to the inner faces of the side bars 10. These supporting rollers, it will be noted, extend only slightly below the side bars as it is desirable not to have the frame of the truck raised much more than is necessary to just clear the floor, thereby permitting the load of sheets or 65 plates to be better discharged on the floor of the heating chamber, as hereinafter described. Extending across the truck frame is another series of rollers, four in number in the construction shown, each one of the 70 latter series of rollers being indicated by 17. These rollers 17, with the exception of the rearmost one, have their ends journaled in plates 18 secured to the inner faces of the side bars, and the rearmost one has its 75 ends journaled in the rearmost plates 16, which last-named plates, it will be noted, are materially larger than the others, being made so merely for convenience in construction. This second-mentioned set of 80 rollers 17 project slightly above the frame-supporting set of rollers, and these rollers 17 are provided for the purpose of affording a support for the several sheets or plates which the truck is intended to carry. As 85 stated, the sheets or plates are held on edge on the truck and, as will be well understood, the supporting rollers 17 upon which they rest permit them to be moved longitudinally of the truck with rapidity and ease. A 90 number of sheets or plates are shown in the drawings and are there indicated by the numeral 19.

To maintain them in edgewise position on the track I provide a plurality of series 105 of swing fingers 20—two such series being

employed in the construction shown. In the construction shown the inner end of each finger 20 has formed on its lower or inner end an eye, and in each eye is clamped by a 5 set bolt 21 a short sleeve 22. These sleeves 22 are rotatably mounted on the shafts 23, the ends of such shafts being supported in suitable plates or brackets secured to the inner faces of the side bars 10. The sleeves 10 22 are of such length that when set in place end to end, as clearly shown in Fig. 1, they serve as means for holding the fingers on each shaft spaced apart sufficiently to properly receive between them the sheets or 15 plates, and by this construction each finger is adapted to be swung into and out of operative position independently—which is of advantage when loading the truck from one side as distinguished from shoving the 20 sheets or plates into place from the open rear end of the truck.

Positioned adjacent to and slightly above each shaft 23 is a cross-bar 24 which will act as a stop for the fingers on the adjacent 25 shaft when such fingers have been turned to a substantially vertical position. By reason of the provision of such stops it is evident that the fingers can not be swung too far forward to prevent acting as holding and 30 separating means for the sheets or plates. The fingers of the two series are, of course, arranged alike so that the spaces between the fingers of one series and those between the fingers of the other series are in alignment 35 for the proper reception of sheets or plates. In order to afford proper support for the outermost sheets or plates I provide other pivoted fingers, indicated by 25,—two at each side of the truck frame in the construction shown. Each of these fingers 25 when down rests in a recess cut in the edge of one of the side bars 10, and each is pivoted in place at 26. The enlarged end where such pivot 26 passes through is, as 40 shown, located in a correspondingly enlarged recess in the side bar, and which, by reason of its shape, while allowing the finger to swing down in a rearwardly direction so as to be practically flush with the 45 upper edge of the side bar, will prevent the finger when turned upward from passing much, if any, beyond a substantially vertical position. Thus these outer fingers, like the fingers 20, can not be swung forward 50 out of a substantially vertical position, although all of the fingers can be readily turned down into inoperative position when the truck is being unloaded, as will appear more clearly when the manner of unloading 55 the truck is described.

27 indicates a spreader device, a plurality of which are preferably employed, for engaging the plates, and, like the fingers hereinbefore referred to, holding such plates on 60 edge and spaced apart. They are placed on

the sheets or plates after the truck has been loaded and are provided for the purpose of maintaining the sheets or plates in their vertical spaced-apart position after the truck has been withdrawn from under them. 70 Each of these spreaders combines a cross-bar with a series of teeth depending therefrom, in the spaces between which teeth the sheets or plates extend, as will be understood, and it is evident that when a plurality 75 of these devices 27 are in engagement with the sheets or plates such sheets or plates will rest as a unit squarely upon the floor of the heating chamber with properly maintained spaces between them for the reception 80 of the carbonizing material that will be employed. The cross-bar of each of these spreader devices is shown as provided with an integral eye 28 into which a hook-shaped implement may be engaged to disengage the 85 spreader from the series of sheets or plates.

In operation a truck loaded with sheets or plates in the manner stated will be rolled into the heating chamber of a furnace, the floor of which, of course, will be on a level 90 with the floor upon which the truck was loaded. The truck will be backed in and when wholly within the chamber a bar or some other suitable holding means will be forced against the ends of the sheets or 95 plates that lie adjacent to the doorway through which the truck was moved, and thereafter the truck will be pulled out of the chamber from beneath the sheets or plates, such movement of the truck being 100 effected, in the construction shown, by the engagement of a hooked rod with an eye suitably secured to the cross-bar 11 of the frame. As the withdrawal of the truck commences the friction of the sheets or 105 plates against the various pivoted fingers will cause such fingers to turn down into the position represented in Fig. 3 so that they can offer no obstruction to the free separation of the truck from its load by reason 110 of the spreader devices coming in contact with them. If for any reason, however, they should not be turned down before a spreader device comes in contact with them the pressure exerted by the spreader device 115 against them would cause them to turn down out of the way. As the truck is pulled out from under its load the sheets or plates will gradually tilt downward over the rear load-supporting roller of the truck 120 and come gently in contact with the floor of the chamber, and inasmuch as the drop of the load from the truck to the floor, when the truck is wholly removed, is but a short 125 one the jar or shock to the sheets or plates will not be such as to disturb the position given them when loading upon the truck and they will, therefore, remain separated and on edge and securely so held by the spreader devices so that the carbonizing ma- 130

terial that is to be thereafter applied to them through an opening in the wall of the chamber can be distributed evenly and effectively and in contact with the surfaces 5 of both sides of each sheet or plate.

What I claim as my invention and desire to secure by Letters Patent, is—

1. In a furnace-charging truck, the combination with a frame comprising a pair of 10 side bars connected together, of rolling supporting means for the frame, other rolling supports for the load on the truck to rest upon, and a plurality of hinged fingers spaced a distance apart for maintaining in 15 spaced relation a plurality of sheets or plates standing on edge on the truck.

2. In a furnace-charging truck, the combination with a frame comprising a pair of side bars connected together, of rolling 20 supporting means for the frame, other rolling supports for the load on the truck to rest upon, a plurality of hinged fingers spaced a distance apart for maintaining in 25 spaced relation a plurality of sheets or plates standing on edge on the truck, and means for preventing said fingers from swinging down in one direction out of operative position.

3. In a furnace-charging truck, the combination with a frame comprising a pair of side bars connected together, of rolling supporting means for the frame, other rolling supports for the load on the truck to rest upon, a plurality of hinged fingers 35 spaced a distance apart for maintaining in spaced relation a plurality of sheets or plates standing on edge on the truck, and a cross-piece extending between the side bars of the frame and adjacent to the hinged 40 ends of the fingers, said cross-piece acting as a stop to prevent downward movement of the fingers in one direction.

4. In a furnace-charging truck, the combination with a frame comprising a pair of 45 side bars connected together, of rolling supporting means for the frame, and a plurality of upstanding separated fingers pivotally connected with the frame for receiving between them a plurality of sheets or 50 plates standing on edge, said fingers being automatically turned down out of operative position when the truck is moved relatively to its load in one direction.

5. In a furnace-charging truck, the combination with a frame comprising a pair of side bars connected together, of rolling supporting means for the frame, other rolling supports for the load on the truck to rest upon, and a plurality of separated fingers 60 pivotally connected with the frame for receiving between them a plurality of sheets or plates standing on edge, said fingers being automatically turned down out of operative position when the truck is moved 65 relative to its load in one direction.

6. In a furnace-charging truck, the combination with a frame comprising a pair of side bars connected together, of rolling supporting means for the frame, a shaft supported between said side bars, and a plurality of upstanding separated fingers having laterally-extending hubs rotatably mounted on the shaft and said fingers being adapted to receive between them a plurality of sheets or plates standing on edge, said hubs being 70 adapted to rock and turn the fingers out of operative position when the truck is moved relatively to its load in one direction, said turning of the hubs being caused by frictional engagement of the fingers with the 75 sheets or plates as said relative movement occurs.

7. In a furnace-charging truck, the combination with a frame comprising a pair of side bars connected together, of rolling supporting means for the frame, a shaft supported between said side bars, and a plurality of upstanding separated fingers having laterally-extending hubs rotatably mounted on the shaft and said fingers being 80 adapted to receive between them a plurality of sheets or plates standing on edge, said hubs and their attached fingers being adapted to turn to swing said fingers downward out of operative position toward one end of 85 the truck when the truck is moved relatively to its load in one direction, and means for positively preventing turning of the fingers toward the other end of the truck.

8. In a furnace-charging truck, the combination with a frame comprising a pair of side bars connected together, of a plurality of rollers journaled in said side bars and acting to movably support the truck, other rollers also journaled in said side bars and 90 extending above said first-named rollers and forming a supporting means for the load on the truck to rest upon, and a plurality of series of hinged fingers arranged transversely of the truck, the fingers of each series being 95 similarly spaced apart for maintaining in spaced relation a plurality of sheets or plates standing on edge on said second series of rollers.

9. In a furnace-charging truck, the combination with a frame comprising a pair of side bars connected together, of a plurality of rollers journaled in said side bars and acting to movably support the truck, other rollers also journaled in said side bars and 100 extending above said first-named rollers and forming a supporting means for the load on the truck to rest upon, a plurality of series of hinged fingers arranged transversely of the truck, the fingers of each series being 105 similarly spaced apart for maintaining in spaced relation a plurality of sheets or plates standing on edge on said second series of rollers, and means for preventing said fingers from swinging down toward one end 110

115

120

125

130

of the truck but permitting such swinging toward the other end thereof when the truck is moved relatively to its load.

10. Means for depositing in the heating chamber of a furnace a plurality of sheets or plates standing on edge, said means comprising in combination a truck provided with means for holding said sheets or plates in spaced relation, and other means coöperating with said holding means on the truck, said other means engaging over the edges of the sheets or plates and maintaining them in said spaced relation after the withdrawal of the truck.
15. 11. Means for depositing in the heating chamber of a furnace a plurality of sheets or plates standing on edge, said means comprising in combination a truck provided with means for holding said sheets or plates in spaced relation, and a device carried by the sheets or plates while on the truck and coöperating to hold the sheets or plates spaced apart and preserving them as a unit in such condition after the withdrawal of the truck.
20. 12. Means for depositing in the heating chamber of a furnace a plurality of sheets or plates standing on edge, said means comprising a truck having a plurality of swing-

ing fingers spaced a distance apart and arranged transversely of the truck and adapted to receive and hold between them said sheets or plates and also adapted to be automatically swung downward out of supporting position when the truck is withdrawn from beneath its load, in combination with a member for engaging the upper portions of said sheets and maintaining them in their spaced relation on the truck after the swinging out of supporting position of the fingers and after the truck has been withdrawn from beneath its load.

13. Means for depositing in the heating chamber of a furnace a plurality of sheets or plates standing on edge, said means comprising in combination a truck provided with means for holding said sheets or plates in spaced relation, and a device carried by the sheets or plates while on the truck and coöperating to hold the sheets or plates spaced apart and preserving them as a unit in such condition after the withdrawal of the truck, said member consisting of a toothed bar, the teeth of said bar extending down against the sides of the sheets or plates.

THEODORE G. SELLECK.
